Primary Examiner — Robert Delehanty(74) *Attorney, Agent, or Firm* — Ulmer & Berne LLP(57) **CLAIM**

The ornamental design for a bathtub closure, as shown and described.

DESCRIPTION

FIG. 1 is a front perspective view of a bathtub closure, showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a front perspective exploded view thereof.

The broken lines in the figures illustrate unclaimed portions of the bathtub closure.

1 Claim, 6 Drawing Sheets(56)
